(57) **CLAIM**

The ornamental design for a vehicle exhaust aftertreatment device cleaning tool, as shown and described.

DESCRIPTION

FIG. 1 is a top perspective view of a first embodiment of a vehicle exhaust aftertreatment device cleaning tool in accordance with the present invention;

FIG. 2 is a left side elevational view of the vehicle exhaust aftertreatment device cleaning tool shown in FIG. 1; FIG. 3 is a right side elevational view of the vehicle exhaust aftertreatment device cleaning tool shown in FIG. 1; FIG. 4 is a front elevational view of the vehicle exhaust aftertreatment device cleaning tool shown in FIG. 1; FIG. 5 is a back elevational view of the vehicle exhaust aftertreatment device cleaning tool shown in FIG. 1; FIG. 6 is a top view of the vehicle exhaust aftertreatment device cleaning tool shown in FIG. 1;

FIG. 7 is a bottom view of the vehicle exhaust aftertreatment device cleaning tool shown in FIG. 1; and

FIG. 8 is a bottom perspective view of the vehicle exhaust aftertreatment device cleaning tool shown in FIG. 1.

FIG. 9 is a top perspective view of a second embodiment of a vehicle exhaust aftertreatment device cleaning tool in accordance with the present invention;

FIG. 10 is a left side elevational view of the vehicle exhaust aftertreatment device cleaning tool shown in FIG. 9;

FIG. 11 is a right side elevational view of the vehicle exhaust aftertreatment device cleaning tool shown in FIG. 9;

FIG. 12 is a front elevational view of the vehicle exhaust aftertreatment device cleaning tool shown in FIG. 9;

FIG. 13 is a back elevational view of the vehicle exhaust aftertreatment device cleaning tool shown in FIG. 9;

FIG. 14 is a top view of the vehicle exhaust aftertreatment device cleaning tool shown in FIG. 9;

(Continued)

FIG. 15 is a bottom view of the vehicle exhaust aftertreatment device cleaning tool shown in FIG. 9; and, FIG. 16 is a bottom perspective view of the vehicle exhaust aftertreatment device cleaning tool shown in FIG. 9. The dashed broken lines in FIG. 9, FIG. 14, FIG. 15, and FIG. 16 show portions of the vehicle exhaust aftertreatment device cleaning tool that form no part of the claimed design. The shade lines in the figures show contour and not surface ornamentation.

1 Claim, 10 Drawing Sheets
